APPARATUS FOR CONDENSING
HYDROCARBONS

John C. Mahoney, Elizabeth, N. J., assignor to
Alco Products, Incorporated, New York, N. Y.,
a corporation of Delaware

Original application March 4, 1931, Serial No.
520,073. Divided and this application Janu-
ary 28, 1933. Serial No. 654,015

13 Claims. (Cl. 257—42)

My invention relates to the art of distilling hydrocarbons and particularly to the condensation of oil vapors and the disengagement of entrained condensate from the uncondensed vapor.

8 This application is a division of my co-pending application, Serial No. 520,073, filed March 4, 1931 now Patent No. 1,918,608 issued July 18, 1933.

One object of my invention is to provide an improved condensing structure in which hydro-
10 carbon vapors are efficiently condensed.

Another object of my invention is to provide a structure for condensing a hydrocarbon vapor out of a mixture with steam and separately condensing the steam.

15 Another object of my invention is to provide a condensing structure for hydrocarbon vapors in which the condensate is formed in two separate condensing zones whereby condensates of different boiling ranges may be obtained from a body 20 of hydrocarbon vapors.

Another object of my invention is to provide an apparatus which is cheaper to build and easier to maintain.

Other objects of my invention will appear from 25 the following description.

In the accompanying drawings which form part of the instant specification and which are to be read in conjunction therewith;

Figure 1 shows a sectional elevation of an ap- 30 paratus embodying one mode of carrying out my invention.

Figure 2 is a sectional view of a modification embodying another mode of carrying out my invention.

35 Figure 3 is a sectional view taken on the line 2—2 of Figure 1.

Figure 4 is a sectional view taken on the line 4—4 of Figure 3.

Figure 5 is a sectional view taken on the line 40 5—5 of Figure 3.

In general, my invention contemplates the provision of a casing with an internal inverted baffle or hood within which are disposed banks of condenser tubes. The construction is such that the tubes are removable for cleaning and repair. The 45 vapors which condense collect in the bottom of the casing from which they are withdrawn through a line which may be governed by a flow controller. The uncondensed vapors which may 50 be hydrocarbon vapors, mixtures of hydrocarbon gas and steam or other vapors, pass upwardly into heat exchanging relationship with a second bank of condenser tubes. The condensate which is formed in the second bank is collected in a receiver disposed under the tube bank and is with-

drawn. It will be understood that the condensate which is withdrawn from the lower part of the shell is of higher boiling point than that withdrawn from the secondary condensate receiver. It is to be understood, of course, that the shell 60 may be placed under a vacuum by means of a suitable pump or other vacuum producing means such as steam jets. Inasmuch as these devices are well known in the art, they have not been shown.

More particularly referring now to the drawings, a shell 1 which may be cylindrical or rectangular as desired, is provided with a plurality of condensing units which are secured thereto in any suitable manner. The lower part 2 of the shell 1 is devoid of tubes and forms a condensate receiver from which the condensate is withdrawn through line 3a which may be controlled by any suitable float control means not shown. Transversely of the shell are positioned a plurality of heat exchange tube bundles 3 and 4.

The tubes extend from a stationary tube sheet 5 to a floating tube sheet 6. Cover sections 7 for the stationary tube sheet 5 form liquid headers or channels 8 which are provided with suitable baffles 9, and inlet and outlet nozzles 10. The floating tube sheet 6 is provided with cover section 11 to form floating headers 12. The floating headers are covered by suitable cover sections 13. The tube bundles 3 and 4 are connected to each other by means of cross 75 connection 14 which extends between respective stationary headers. The cooling medium may enter the upper nozzle 15 or the lower nozzle 10, depending on whether or not counter- or concurrent flow is desired. The upper part of the 80 shell 1 supports a casing 16 which is provided with a stationary tube sheet 17 and into which tubes 18 are expanded. The lower portion of the tubes 18 are secured to a floating tube sheet 19 which is provided with a cover section 20 to 85 form a floating header. A cover section 21 provided with a suitable baffle 22 and a stationary tube sheet 17 is secured above the tube sheet 17, the said cover having inlet and outlet openings 23 and 24. Casing 16 projects downwardly into 100 the shell 1 and forms at its lower portion a condensate receiving basin 25 having a drawoff outlet 33. It is provided with a peripheral series of openings 26, which may vary in size and shape depending upon the volume of vapor present. 105 The upper portion of the casing 16 communicates with the nozzle 30 which leads to any suitable vacuum producing means such as an air pump or steam jets. It is to be understood, of course, that the apparatus may be operated under at- 110

mospheric, sub-atmospheric, or super-atmospheric pressures, depending upon process conditions.

Within the shell 1 I position an inverted baffle 5 or hood 31 which is in the form of an elongated closed housing open at the bottom thereof. This baffle may be of any suitable form. The housing 31, which I will hereinafter refer to as a hood baffle, is spaced from the shell 1 in the form 10 shown in Figures 1, 3, 4, and 5 to form a segmental passageway therewith. The tube bundles 3 and 4 may extend through the inverted baffle in the form shown in Figure 2 as can be readily seen by reference to the drawings. In this form, 15 the space between the baffle and the shell is annular.

A vapor inlet nozzle 32 leads to the upper portion of the inverted baffle 31. A condensate drawoff line 3a leads from the condensate receiver 2.

In operation, water or other cooling medium may be introduced through nozzle 23 of the upper condensing member and leave the same through nozzle 24 from which it may be led to 25 the inlet pipe 10 of the lower tube bundle 4, thence through cross connection 14, through tube bundle 3, and finally be discharged through pipe 15. Separate and individual cooling medium circuits may also be maintained in each tube bundle 30 by suitably modifying the interconnecting piping. The vapors may enter through nozzle 32, flow downwardly in contact with tube bundles 3 and 4 in series, then upwardly through the segmental spaces between the hood baffle 31 and 35 the shell 1 through the openings 26 of the casing 16 into contact with the tubes 18 of the upper condensing member. It will be noted that the flow of the vapors is countercurrent to the flow of the cooling medium. By simply reversing the 40 point of inlet, the flow of the cooling medium and of the vapors may be concurrent, if desired.

It is to be understood, of course, that baffles or distributing members may be positioned within the hood baffle 31 to distribute the vapors over 45 the surface of the condensing tubes 3. The condensate falling downwardly washes the tubes of the tube bundles 3 and 4 and tends to keep them free of tarry deposits. It will be understood, of course, that the high boiling components of 50 the vapors will be condensed by tubes 3 and 4. This condensate will collect in the receiver 2 and will be withdrawn through connection 3a. The uncondensed vapors will rise upwardly in the segmental spaces formed by the hood baffle 31 and the shell 1 and enter the casing 16 through 55 the openings 26. Here certain components of the vapors are condensed by heat exchange with the medium flowing through the tubes 18. This condensate will be of a lower boiling composition 60 than that which collects in the lower receiver 2. This condensate is collected in the receiver 25 and is withdrawn through line 33. The uncondensed vapors and fixed gases pass out of my device through line 30 which, as was pointed out 65 above, may be connected to an air pump or vacuum jets if desired. If required, additional condensing equipment may be positioned between line 30 and the vacuum jets.

It will be manifest that I have accomplished 70 the objects of my invention. I am enabled to condense hydrocarbon vapors in an expeditious manner and obtain fractional condensates or to separately condense the steam from a hydrocarbon vapor-steam mixture. My apparatus is easily maintained inasmuch as all of the tube bun-

dles are removable independently of the other tube bundles. The flow of the vapors may be countercurrent throughout the entire assembly, concurrent throughout the entire assembly, or concurrent in part and countercurrent in another part, depending upon the connections between the various tube nests. Close control of the condensing temperatures may be effected. It is to be understood, of course, that while I have shown two tube bundles under the hood baffle that any suitable number of tube bundles may be employed.

It will be understood that certain features and sub-combinations are of utility and may be employed without reference to other features and sub-combinations. This is contemplated by and is within the scope of my claims. It is further obvious that various changes may be made in details within the scope of my claims without departing from the spirit of my invention. It is, therefore, to be understood that my invention is not to be limited to the specific details shown and described.

Having thus described my invention, what I claim is:

1. An apparatus for condensing hydrocarbon vapor mixtures comprising a vertical shell; a coil unit within said shell, means for introducing hydrocarbon vapor above said cooling unit and means for directing the vapor downwardly over 105 the unit to the lower portion of the shell and upwardly to the upper portion of the same independently of the downflowing vapor.

2. An apparatus for condensing hydrocarbon vapor and the like, comprising a vertical shell having an inlet opening in its upper portion and a condensate outlet opening in its bottom portion; a cooling unit disposed within said shell; means for directing the flow of vapor from said inlet opening, over the cooling unit to the lower 110 portion of the shell and for changing the course of the vapor at the said lower portion of the shell and directing the same upwardly at the sides of the cooling unit, to the upper portion of said shell.

3. An apparatus for condensing hydrocarbon vapor and the like comprising a vertical shell having an inlet opening near the top of the same; a cooling unit transversely disposed in the upper portion of said shell; a baffle structure disposed so as to enclose said unit within said shell and 125 adapted to direct the flow of vapor over said unit, said shell having a condensate outlet opening in its lower portion below said cooling unit, and said baffle structure providing a space between the cooling unit and the shell to permit 130 the upward passage of vapor from the said lower portion of the shell to the upper portion of the same.

4. An apparatus for condensing hydrocarbon vapor comprising a vertical shell; a cooling unit 135 transversely disposed within said shell; means for introducing hydrocarbon vapor above said cooling unit, means for directing the vapor downwardly over the unit to the lower portion of the shell; and for directing said vapor from the said lower portion of the shell to the upper portion of the same independently of the downflowing vapor; the lower portion of the shell serving as a condensate receiver and condensing means disposed at the upper part of said shell.

5. An apparatus for condensing hydrocarbon vapor and the like, comprising a vertical shell having an inlet opening near the top of the same; a cooling unit transversely disposed in the upper portion of said shell, a baffle disposed above and 140

- at the sides of said unit within said shell and adapted to direct the flow of vapor over said unit, said shell having an outlet opening in its lower portion below said cooling unit, said baffle 5 providing a space at the side of said shell to permit the upward passage of vapor from the said lower portion of the shell to the upper portion of the same; and vapor condensing means disposed at the upper end of said shell.
- 10 6. An apparatus for condensing hydrocarbon vapor and the like, comprising a vertical, substantially cylindrical shell having an inlet opening near the top of the same; a cooling unit transversely disposed in its upper portion, the lower portion of said shell embodying a condensate receiving zone and having an outlet opening for liquid condensate; baffle plates disposed above and at the sides of the cooling unit adapted to direct the flow of vapor from the said inlet port over said cooling unit, said baffles providing segmental spaces at the sides of said unit permitting the upward passage of vapor from the lower portion of the shell to the upper part of the same.
- 15 7. An apparatus for condensing hydrocarbon vapor and the like, comprising a vertical substantially cylindrical shell; a cooling unit transversely disposed within the upper portion of the shell; baffling means above and at the sides of said cooling unit; means for introducing hydrocarbon vapor above the cooling unit within said baffles, said baffles at the sides of said cooling unit providing passageways at the sides of the said cylindrical shell adapted to permit the passage of vapor from the lower portion of the shell to the upper portion 20 of the same; and condensing means disposed above the said upper baffle.
- 25 8. An apparatus for condensing hydrocarbon vapor and the like, comprising a vertical substantially cylindrical shell having an inlet opening near the top of the same; a cooling unit transversely disposed in its upper portion, the lower portion of said shell embodying a condensate receiving zone and having an outlet opening for liquid condensate; baffle plates disposed above and at the sides of the cooling unit adapted to direct the flow of vapor from the said inlet port over said cooling unit, said baffles providing segmental spaces at the sides of said unit, permitting the upward passage of residuary undensed vapor from the lower portion of the shell 30 35 40 45 50
- to the upper part of the same; means in the upper part of said shell above the said inlet opening for condensing the said residuary vapor; and means for separately withdrawing the condensate from the receiving zone of the shell, the condensate of the residuary vapor, and the non-condensed vapor.
- 55 9. An apparatus for condensing hydrocarbon vapor and the like, comprising a vertical substantially cylindrical shell; a cooling unit transversely disposed within the upper portion of the shell; baffling means above and at the sides of said cooling unit; means for introducing hydrocarbon vapor above the cooling unit within said baffles, said baffles at the sides of said cooling unit providing passageways at the sides of the cylindrical shell, adapted to permit the upward passage of vapor from the lower portion of the shell to the upper portion of the same.
- 60 10. An apparatus for condensing vaporized hydrocarbons and the like, comprising a vertical shell, a plurality of heat exchangers removably positioned in said shell, a baffle partially surrounding said heat exchangers and forming a hood having its lower portion open and extending downwardly into the lower portion of said shell, said lower portion of the shell forming a receiver for the condensate and permitting it to collect in a pool, means for withdrawing the condensate from said pool, means for introducing vaporized hydrocarbons into said hood forming baffle, and means disposed above said heat exchangers adapted to condense the uncondensed portions of said vaporized hydrocarbons.
- 65 11. A condenser as in claim 10, wherein said hood forming baffle is spaced inwardly of said shell to form a passage for the uncondensed vapors leading to said condensing means.
- 70 12. A condenser as in claim 10, in which a condensate receiving means is disposed below said condensing means, an outlet for the condensate, and an outlet for the uncondensed portions of the vapors.
- 75 13. An apparatus for condensing hydrocarbon vapors comprising in combination a shell, an inverted baffle within the shell in spaced relation therewith, condenser tubes extending through said baffle and means for introducing hydrocarbon vapors into said baffle.
